UNITED STATES PATENT OFFICE.

ALFRED H. HOFER, OF DAYTON, OHIO, AND LUKE T. WICKEY, OF LOS ANGELES, CALIFORNIA.

STEERING MECHANISM.

1,385,785.

Specification of Letters Patent. Patented July 26, 1921.

Application filed October 25, 1920. Serial No. 419,481.

To all whom it may concern:

Be it known that we, ALFRED H. HOFER and LUKE T. WICKEY, citizens of the United States of America, residing at Dayton, 5 Montgomery Co., Ohio, and at Los Angeles, county of Los Angeles and State of California, respectively, have invented a certain new and useful Improvement in Steering Mechanism, of which the following is a 10 specification.

Our invention relates to steering mechanism particularly designed for aircraft in general, the broad object in view being to provide an irreversible self-locking rudder 15 operating member which will remain in any position in which it is set, holding the rudder locked in a corresponding position and thereby relieving the aviator from physical and mental strain while flying on a 20 straight away course.

The invention is particularly valuable when flying in cross winds or under any condition where it is necessary to maintain the vertical rudder at an angle to the normal 25 path of flight and at an angle to the longitudinal axis of the machine.

A further object of the invention is to provide in conjunction with a rudder controlling member, usually consisting of what 30 is known in the art as a foot bar, an automatic clutch which will enable such foot bar to be readily moved by the aviator in the usual way for turning the rudder and yet upon removal of foot pressure will lock the 35 rudder controlling member in a temporarily fixed position until the clutch is released by the operation of the foot bar. The steering mechanism may then be operated in the usual way by the aviator for turning the 40 vertical rudder to any desired angle. The device herein shown and described is also valuable to compensate for the slight unbalance of the airplane for example due to the reaction of the propeller on the aerofoil 45 surfaces.

With the above and other objects in view, our invention consists in the novel construction, combination and arrangement herein shown, described and claimed.

50 In the accompanying drawings:

Figure 1 is a plan view of the improved steering mechanism;

Fig. 2 is a longitudinal section through the same;

55 Fig. 3 is a horizontal section through the

center portion of the device showing the clutch mechanism;

Fig. 4 is a detail view of the manually operated member;

Fig. 5 is a detail view of the rudder operating member.

In the standard steering mechanism now employed in airplanes, what is known as a foot bar is used, said foot bar being the initial controlling element for the vertical rudder. This member is manually operated and is hereinafter termed the manually operated member, the same being indicated in the drawing by reference character 1.

In carrying out the present invention I 70 employ in addition to the manually operated member or foot bar 1 a rudder operating member or bar 2. Both of the members 1 and 2 consist of two armed levers and both are mounted on a common central pivot 75 member 3 to turn or oscillate thereon. The rudder operating member 2 is coupled by the connections 4 such as cables, to the rudder head or cross bar on the vertical rudder, not shown, the vertical rudder with its cross 80 head being of well known construction and arrangement and forming part of the empennage of the airplane.

Associated with the members 1 and 2, is clutch mechanism for locking the member 2 85 and thereby locking the vertical rudder against movement. Said clutch mechanism embodies a stationary or fixed annular clutch member 5 which is secured to a supporting bracket 6 fastened within the fuselage of 90 the machine. The clutch mechanism also embodies a centrally arranged cam 7 which is permanently fastened with two flat head screws and moves with the rudder operating member 2. Between the cam 7 and the annular clutch member 5 are movable clutch members 8 shown in the form of balls or rollers which bear against both the cam 7 and the annular clutch member 5. The balls or movable clutch member 8 are arranged in 100 pairs and between the balls of each pair there is arranged a thrust spring 9. This spring serves to press the balls 8 away from each other and into contact with the fixed clutch member 5 so that instantaneous gripping or clutching operation will take place 105 between the cam 7 and the clutch member 5 when there is a tendency to turn the rudder operating bar 2 and consequently the cam 7.

105

110

The manually operated member 1 has projecting therefrom dogs 10 shown in the form of segmental lugs which extend within the annular clutch member 5 and between 5 the pairs of movable clutch members 8. The function of the dogs 10 is to partially displace certain movable clutch members 8 and carry them to the direction in which 10 manually operated member 1 is turned, thereby releasing the clutch mechanism to permit the rudder operating bar 2 to be turned by manually operated member 1. In order to insure this operation, the segmental 15 slots in rudder operating member 2, are longer than the segmental dogs 10, which permits manually operated member 1 to rotate sufficiently to release the ball clutch members 8; further rotation of manually 20 operated member 1 will rotate rudder operating member 2. It is to be understood that the cam 7 is loose with respect to pivot pin 3 so that it may turn thereon and it is to be further understood that the segmental 25 slots in rudder operating member 2 are sufficiently larger than dogs 10 to allow a small amount of play. This permits the dogs 10 to displace the balls 8 ahead of them, before cam 7 begins to turn under the propelling action of the member 1.

30 The operation of the mechanism may be described as follows:

The pilot pushes on the manually operated member 1 at either of the end portions thereof, causing the movement of cam 7 and 35 the rudder operating member 2 and consequently causing movement of the vertical rudder of the aircraft. When the pilot pushes on the member 1 and starts to turn the same, the dogs 10 press against opposite 40 movable clutch members or balls 8, there being no clutching action during this movement. The other balls 8 are propelled by the dogs 10 due to the action of the springs 9. Such is the action when the manually 45 operated member 1 is actuated by the foot of the pilot. As soon as the foot of the pilot is removed from the member 1, due to wind pressure on the rudder, the latter of course tends to return to its normal position. This tendency is transmitted to cam 50 7. The cam now tries to turn backwardly to its normal position, but due to the action of springs 9, the balls 8 are jammed against the stationary annular clutch member 5.

55 The rudder operating member 2 is thereby securely locked against movement, as is also the vertical rudder.

When it is desired to release the clutch, pressure is brought to bear on the member 60 1 by the pilot's foot at the opposite end from that which originally actuated the dogs 10 causing said dogs, which are in fact unlocking dogs, to thrust said balls out of clutching engagement with the cam 7 and the stationary clutch member 5, pushing the dogs 65

along a circular path at the same rate as the cam is moved. The clutch is thus released so that the vertical rudder may be moved to the new position where it will be automatically locked upon the removal of 70 the pilot's foot from the rudder operating bar 1.

While the clutch mechanism is shown applied to the rudder controlling or steering means, it is to be understood that the mechanism above described may also be used for controlling other parts of the machine such as the ailerons, engine controls and other devices which will suggest themselves. 75

What I claim is:

1. Irreversible self-locking steering mechanism for aircraft, embodying in combination, a centrally pivoted foot-operable steering bar, a centrally pivoted rudder operating bar, a cam operable by and having a 85 fixed relation to said rudder-operating bar, an annular stationary clutch member, a movable clutch member adapted to effect a locking engagement between said cam and stationary clutch member, and means on said 90 foot operable steering bar to release said movable clutch member.

2. Irreversible self-locking steering mechanism for aircraft, embodying in combination, a centrally pivoted foot-operable steering bar, a centrally pivoted rudder operating bar lying parallel to said steering bar, a cam operable by and having a fixed relation to said rudder-operating bar, an annular stationary clutch member, a movable 100 clutch member adapted to effect a locking engagement between said cam and stationary clutch member, and means on said foot operable steering bar to release said movable clutch member. 105

3. Irreversible self-locking steering mechanism for aircraft, embodying in combination, a centrally pivoted foot-operable steering bar, a centrally pivoted rudder operating bar, a cam operable by and having a 110 fixed relation to said rudder-operating bar, and having an eccentric peripheral working face, an annular stationary clutch member, a movable clutch member adapted to effect a locking engagement between said cam and stationary clutch member, and means on said 115 foot operable steering bar to release said movable clutch member.

4. Irreversible self-locking steering mechanism for aircraft, embodying in combination, a centrally pivoted foot-operable steering bar, a centrally pivoted rudder operating bar, a cam operable by and having a fixed relation to said rudder-operating bar, an annular stationary clutch member having an internal working face concentric to the pivots of the foot-operable steering bar and the rudder-operating bar, a movable clutch member adapted to effect a locking engagement between said cam and station- 125 130

ary clutch member, and means on said foot operable steering bar to release said movable clutch member.

5. Irreversible self-locking steering mechanism for aircraft, embodying in combination, a centrally pivoted foot-operable steering bar, a centrally pivoted rudder operating bar, a cam operable by and having a fixed relation to said rudder-operating bar,
10 an annular stationary clutch member, said cam being arranged to operate within the

annular stationary clutch member, a movable clutch member adapted to effect a locking engagement between said cam and stationary clutch member, and means on said 15 foot-operable steering bar to release said movable clutch member.

In testimony whereof we affix our signatures.

ALFRED H. HOFER.
LUKE T. WICKEY.
